17 Claims. (Cl. 170—160)

1

This invention relates in general to devices for propelling airplanes and the like.

Among the objects of the present invention it is aimed to provide propelling devices for airplanes and the like which can be driven at high velocities which may equal or even exceed the local velocity of sound.

With this main object in mind, the present invention aims to provide an improved propeller consisting of a plurality of flexible blades, with each blade held in the correct position relative to the air stream by aerodynamic and centrifugal forces.

It is still another object of the present invention to provide, in the interest of producing propelling devices for use at extremely high altitudes, blades, the lengths of which may be increased at will to compensate for the decreasing thrust and power at increasing altitudes.

It is still another object of the present invention to provide a blade which will operate equally well in the subsonic and the supersonic ranges of velocity.

More specifically, it is an object of the invention to provide an improved blade which will operate both in the subsonic and supersonic ranges of velocity which comprehends the use of a blade including two strips of flexible material held in rigid position relative to one another.

These and other features, capabilities and advantages of the invention will appear from the subjoined detail description of specific embodiments thereof illustrated in the accompanying drawings in which

Figure 1 is a longitudinal section of the mechanism for actuating the blades.

Fig. 2 is a section on the line 2—2 of Fig. 1.

Fig. 3 is a section on the line 3—3 of Fig. 1.

Fig. 4 is a plan view on an enlarged scale of one of the blades.

Fig. 5 is a fragmental side elevation of the blade shown in Fig. 4, on a still larger scale than that shown in Fig. 4.

Fig. 6 is a fragmental transverse section of the blade shown in Fig. 5 on a still larger scale.

Fig. 7 is a fragmental transverse section on the line 7—7 of Fig. 9 of a modification disclosing means for protecting the blades against injury.

Fig. 8 is a fragmental plan view of the embodiment shown in Fig. 7.

Fig. 9 is a fragmental longitudinal section of the embodiment shown in Fig. 7.

Fig. 10 is a fragmental view of the blade and protective medium shown in the embodiment of Fig. 7 on a larger scale than that shown in Fig. 7.

2

Fig. 11 is a diagram of the wiring for the control.

Before describing the present invention in detail and in view of the radical departure thereof, it might be well to review briefly the problem involved. The demand for propellers designed to operate at high angular velocity has led to the gradual increase of propeller tip speeds until these are now equal to or in some cases slightly greater than the local velocity of sound. The greatly increased drag of normal airfoil sections at supersonic velocities and the lack of rigidity inherent in very thin blades, however, makes any further increase in the tip velocities impractical for propellers of normal design.

The basic idea of the present improved blade resides in using such thin blades, with a thickness preferably 3% of the width, or less, that the lift-drag ratio and the overall propeller efficiency will remain large even if the propeller tip velocity is far higher than the local velocity of sound. The complete loss of torsional rigidity which this entails is compensated for by the use of aerodynamic forces to maintain each blade at the correct angle of attack relative to the air stream. This angle of attack will remain roughly constant as the airplane or the like varies either its speed or its altitude. A constant angle of attack has as its result a decrease of propeller torque and of power absorbed with increasing altitude or with decreasing speed of the aircraft, the engine R. P. M. remaining constant, but this result can be offset by increasing the radius of the propeller during flight. To this end, see Fig. 3, the blades 1 can be extended by the drum 5 to increase their length, and consequently the propeller radius, to the required extent.

With complete loss of torsional rigidity characterizing such thin blades, the twisting moment arising from centrifugal force becomes important, and tends to decrease the angle of attack, but this difficulty may be overcome by the use of blades whose length greatly exceeds their width. Hence the blades 1 are not only very thin compared to their width, but also very long compared to their width.

A further important feature of the present invention resides, see Fig. 4, in splitting each blade into two parts, namely the two strips 2 and 3, separated by a distance comparable with the blade width, with the two strips held in rigid position relative to one another by the lateral reinforcing ribs 4, and with the leading, or forward, strip roughly twice as thick as the trailing, or rear, strip. The purpose of this design is to keep the

blade at an appropriate angle of attack when the velocity of air past the blade is either less than or greater than the velocity of sound. If the trailing strip 2 is inclined at about 4 degrees to the leading strip 3, the trailing strip 2 will act in the same way as the tail on a conventional airplane, keeping the blade as a whole at a stable positive angle of attack. When the velocity of air past the blade is less than that of sound, the equilibrium angle of attack will be limited to some angle less than about 6 degrees by the turbulence produced at the sharp leading edge of the forward strip, which prevents the air load on the leading strip from increasing beyond a certain limiting value, and which will therefore bring the center of pressure on the blade as a whole back to the middle of the blade for a moderate angle of attack. Since the center of support is some distance in front of the middle, as hereinafter described, the equilibrium angle of attack will not be excessive, for subsonic flow.

When the velocity of the air exceeds that of sound, however, the center of pressure on the blade will move towards the rear of the blade, and the equilibrium angle of attack will be diminished. With a blade made of two strips as hereinafter described, the movement of the center of pressure of the resultant combination, as the air velocity changes from subsonic to supersonic, is a small fraction, roughly 7%, of the width of the blade as a whole. With the aforementioned inclination of 4 degrees of the rear strip 2 relative to the leading strip 3, the average angle of attack for the two strips in supersonic operation will be quite sufficient, about 3 degrees, to give high propeller power with high aerodynamic efficiency.

In the embodiment illustrated in Figs. 1 to 6, inclusive, the blade 1, constituting a main part of the present invention, is assumed, for the example illustrated, to be about 12 feet in length, about two inches wide at its widest length, and consisting of two strips, 2 and 3, integral with one another as shown, and each of about .6 inch in width, connected at intervals of 3 inches by reinforcing ribs 4, integral with the strips and having a cross section of about .02 inch by .10 inch. In Fig. 6 the relative proportions of the ribs 4 to the strips 2 and 3 are shown. It is assumed for the purpose of this example that the greatest thickness of the forward strips 3 will be about .016 inch, while the greatest thickness of the trailing strips 2 will be about .007 inch, each strip tapering off to sharp edges both front and rear. The blade 1 with dimensions such as just set forth will have its center of gravity lie roughly .28 inch forward of the middle of the blade. The reinforcing members, or ribs, 4 will increase the total area of the blade by some 5%, the mass by at most 20%, and if the reinforcing members 4 are made of quenched and tempered nickel-chrome steel like the rest of the blade, as hereinafter to be set forth, then the reinforcing members 4 will have sufficient rigidity to keep the angular inclination of the trailing strip relative to the leading strip constant to within half a degree under an air load of two pounds per square inch. Under normal operation the air load on the trailing strip would be much less than this.

In the foregoing it will be assumed that for propellers designed to operate at higher velocities, those exceeding 1400 feet per second, the base 6 will be considerably increased in thickness. If the material of which the blade 1 were made is composed of quenched and tempered nickel-chrome steel, of which the fatigue strength is about 49

tons per square inch, then with a tip velocity of 2000 feet per second, and a cross section of the base 6 ten times that at the tip 7, with the thickness of the blade increasing gradually from the tip 7 to the base 6, the resulting stress at the base would be about 32 tons per square inch, well below the fatigue limit of quenched and tempered nickel-chrome steel. It has also been found that if the tip velocity is reduced to 1400 feet per second, the cross section at the base need be only twice that at the tip to give a stress of 31 tons per square inch. With this lower velocity, furthermore, the outermost 40% of the blade may be given a uniform cross section. In view of the foregoing the base 6 is merely indicated as increased in thickness as compared to the cross section of the rest of the blade with a view not to be limited to any thickness less than twice the thickness of the blade proper.

20 In any case the total weight of the blade 1 will be not greater than one pound at the most, and for a propeller having 32 blades, as illustrated in Fig. 3, the total weight of all the blades should therefore be less than thirty pounds. The centrifugal force at the base of a single blade would be about one or two tons, if the blade is designed to operate with a tip velocity of not more than 1400 feet per second, while the total thrust would be about 150 pounds at sea level, and less at high altitudes. The thrust and torque would be transmitted to the base or root 6 of the blade and so on to the drum 5 and the shaft 8 by a slight forward inclination of the blade together with a slight lag. The embodiment afore described could apply at least 4000 maximum horsepower at an airplane velocity of 300 miles per hour at sea level, and at least 1500 maximum horsepower at the same velocity at 30,000 feet above sea level.

From the foregoing it will be evident that a propeller made of blades 1 of this type would have numerous advantages. It would operate at airplane velocities up to more than a thousand miles per hour. The maximum power absorbed at any altitude could be made as great as desired, either by increasing the number of blades or by increasing the total length of each blade, since the increase of weight or reduction of propeller efficiency for supersonic operation produced by either change would be very small. Varying the radius of the propeller would give very much more flexibility over a much wider range than is given by the present variable pitch propellers, and has the additional advantage of higher, more uniform efficiency.

55 The main feature of the invention, of course, resides in the discovery of a blade as heretofore described and illustrated in detail in Figs. 3 to 6, inclusive. The part of the invention now to be described, while incidental to this type of blade, is, nevertheless, considered essential as showing one way of using a blade of this type in an airplane.

In Figs. 1, 2 and 3 there is shown a drive shaft 8 which is fixed to the main shell or housing 9 by the splines 10. This shaft 8 is operatively connected to a suitable motor, not shown, which motor in turn is mounted in the frame or body 11 of the airplane in the usual way. To this frame 11 there is secured in the present instance a rigid soft iron annular ring 12 spaced from the rear annular edge 13 of the shell 9. The shell 9, which is preferably about three feet in diameter, has an inner wall or partition 14 through which the shaft 8 extends. To this partition 14, 70 and extending rearwardly therefrom, there is

provided a cylindrical wall 15, having at its rearward end a partition 16 through which the shaft 8 also extends.

Adjacent to the annulus 12 there is rotatively mounted on the shaft 8 the power wheel 17, the hub 18 of which is positioned between the partition 16 and the collar 19 fixed on the shaft 8. The outer cylindrical portion 20 of the power wheel 17 has on its rear face the annular set of magnets 21, 22 and 23, positioned to face the annulus 12 as shown in Fig. 1. The front end of the cylindrical portion 20 is provided with the inclined gear teeth 24 to mesh with the conical gears 25 and 26. The inner periphery of the front end of the cylindrical portion 20 is provided with a plurality of annular sets of magnets 27, 28 and 29, positioned in the present instance adjacent to a plurality of sets of armature windings 30, 31 and 32 on the annulus 33 fixed on the outer periphery of the rear end of the cylindrical partition 15. The set of magnets 21 to 23, inclusive, when energized, will cooperate with the annulus 12 to lock the power wheel 17 in fixed relationship to the frame 11 and against rotation with the shell 9. In turn, when the set of magnets 27, 28 and 29 and armature windings 30, 31 and 32 are energized and the set of magnets 21, 22 and 23 is de-energized, then the set of magnets 27, 28 and 29 will form a shunt wound D. C. motor with the armature windings 30, 31 and 32 to cause the power wheel 17 to rotate relative to the shell 9 in the direction of the arrow 34, see Fig. 2, at a sufficient speed in turn to cause the drum 5 through the train of gears now to be described to rotate at a faster rate of speed than the rate of speed of the shell 9. In other words, when the power wheel 17 is arrested the drum 5 will be retarded relative to the shell 9, although both may be rotating in the same direction relative to the frame 11, to withdraw the blades 1 from extending outside of the shell 9 or segments 35. On the other hand, when the power wheel 17 is caused to rotate more rapidly than the shell 9 by the motor formed by the magnets 27 to 29, inclusive, and the armature windings 30 to 32, inclusive, the drum 5 will be caused to rotate at a faster speed than that of the shell 9 or segments 35 in turn to permit or cause the blades 1 to be extended or extruded from the shell 9 or the segments 35. The train of gears between the power wheel 17 and the drum 5 consists essentially of the following: the teeth 24 meshing with the gear 25 cause the shaft 36 of the gear 25 to be rotated, in turn to cause the worm 37 on the shaft 36 to rotate. The worm 37 being in mesh with the worm wheel 38 on the shaft 39 will cause the small gear 40 fixed to the shaft 39 to rotate and this gear 40, being in mesh with the large gear 41 on the shaft 42, will cause the small gear 43 on the shaft 42 to be rotated. The small gear 43, in turn being in mesh with the large gear 44, rotatably mounted on the shaft 8, will cause the large gear 44 to be rotated relative to the shaft 8 either when the power wheel 17 is arrested relative to the shaft 8, or actuated at a different ultimate speed than that of the shaft 8. The gear 44 as shown in Fig. 1 is integral with the drum 5.

The shaft 36 on which the conical gear 25 and worm 37 are mounted is journaled at one end in the shell 9 and at its other end in the collar or bushing 45 fixed on the shaft 8, see Fig. 2. The shaft 39, see Fig. 1, is journaled at one end in the partition 16 and intermediate the worm wheel 38 and gear 40 is journaled in the par-

tition 14. The shaft 42 is journaled at one end in the partition 14 and at its other end in the partition 46. When the power wheel 17 is neither arrested nor actuated to rotate independent of the shaft 8, but allowed to ride with the shaft 8, then in order to anchor the train of gears just described, including the power wheel 17, against displacement, the anchor or clutch now to be described is provided. This anchor consists of a conical gear 26, see Fig. 1, mounted on the shaft 48 which is journaled at one end as shown in the shell 9 and at its other end is journaled in the projection 52 with the bushing 49 slidably mounted on the shaft 48, but fixed to rotate therewith by the spline 50. The projection 52 has a clutch disc 53 fixed thereto to engage the clutch disc 54 fixed on the bushing 49. These clutch discs 53 and 54 are normally maintained in frictional engagement with one another by the spring 55 tensed between the clutch disc 54 and the inner face of the partition 15. The bushing 49 also has a metal disc 56 constituting an armature disposed outside of the partition 15 and adjacent to the magnet 57 on the shaft 48. From the foregoing it will appear that when the magnet 57 is de-energized the spring 55 will be operative to cause the clutch faces 53 and 54 to engage one another and lock the gear 26 against rotation relative to the shell 9 and thereby similarly lock the power wheel 17 against rotation relative to the shell 9, in turn to anchor the train of gears between the power wheel 17 and drum 5 to rotate as a stationary mass with the shaft 8. On the other hand, as will hereinafter be described, whenever either the magnets 21, 22 and 23 are energized to anchor the power wheel 17 to the annulus 12, or the magnets 27, 28 and 29 and armature windings 30, 31 and 32 are energized to cause the power wheel 17 to rotate relative to the annulus 33, the magnet 57 will be energized to attract the disc 56 against the tension of the spring 55 to de-clutch the faces 53 and 54 and permit the gear 26 to rotate relative to the shell 9; whereby in turn the power wheel 17 will be free to rotate relative to the shell 9.

As aforesaid, the embodiment of the invention illustrated in Figs. 1 to 6, inclusive, is equipped with 32 blades. These are secured to the outer periphery of the drum 5, tangential thereto, so that should the drum 5 be rotated in the direction opposite to that of the arrow 58, the blades 1 may be caused to be wrapped around the drum 5 and upon one another. As shown, the reinforcing strips 4 will extend toward the drum when the blades 1 are wrapped on the drum 5. The shell 9, see Fig. 2, has 32 slots 59 disposed between the partition 46 and the enlargement or radially extending partition 60, see Fig. 1, one slot for each blade 1. These slots are wide enough to enable the blades 1 freely to pass therethrough and also of sufficient depth to clear the reinforcing sections 4. Furthermore, these openings 59 are formed by the segments 35 which have an inner curved surface 61 to engage the free unobstructed faces 62 of the blades 1 as distinguished from the faces of the blades 1 on which the reinforcing sections 4 are mounted. The faces 61 of the segments 35 are curved so as to prevent any abrupt sharp corners engaging the blades 1 as they leave the drum 5 and pass to and beyond the segments 35. These blades 1, while preferably composed of a metal of the highest fatigue strength, such as quenched and tempered nickel-chrome-steel, nevertheless,

on account of their extreme thinness, might bend if they had to pass over sharp edges when leaving the drum 5.

The electrical control for the magnets 21 to 23, inclusive, 27 to 29 inclusive, the armature windings 30 to 32, inclusive, and magnet 57, will now be described. Preferably there is provided a block 80 that is attached to the frame 11, having two brushes 81 and 82 positioned to engage the contact rings 83 and 84, respectively, mounted on the power wheel 17. The brush 81 in the present instance is connected by the conductor 88 to the switch 188, see Fig. 11, which in turn is connected by the conductor 85 to a suitable source of current, the negative side of which will be grounded by the conductor 87 as shown in Fig. 5. The brush 82 in turn is connected by the conductor 89 to the switch 189 which in turn is connected by the conductor 85 to the suitable source of current aforesaid. The ring 83 in turn is connected by the conductor 91 to the magnets 21 to 23, inclusive, which in turn are grounded as indicated, to complete a circuit when the switch 188 is closed. The ring 84 in turn is connected by the conductor 86 to the magnets 27, 28 and 29, inclusive, constituting the field and to the armature windings 30, 31 and 32, inclusive, of a shunt wound D. C. motor which in turn is grounded by the conductor 94 to complete a circuit when the switch 189 is closed.

The magnet 57 in turn is energized and only energized when either the switch 188 is closed to energize the magnets 21 to 23, inclusive, or when the switch 189 is closed to energize the magnets 27 to 29, inclusive, and the armature windings 30, 31 and 32, inclusive. For this reason the conductor 96, passing through the shaft 8, as indicated in Fig. 1, is connected not only by the conductor 95 to the contact 195 of the switch 189, but also by the conductor 97 to the contact 197 of the switch 188. After passing through the shaft 8, as indicated, the conductor 96 is connected to one terminal of the magnet 57, the other terminal of the magnet 57 being connected to ground by the conductor 103.

From the foregoing it will thus appear that when it is desired to retract the blades 1 all or part of the way, it will only be necessary to close the switch 188 when it will engage the contact 197 as well as the contact of the conductor 88 to energize the magnets 21, 22 and 23, inclusive, and also the magnet 57. When the switch 188 is so closed, the power wheel 17 will be anchored to the annulus 12 and the magnet 57 energized to permit the shell 9 to rotate independent of the power wheel 17. On the other hand, when it is desired to extrude the blades 1 all or part of the way it will only be necessary to open the switch 188 and close the switch 189 in turn to energize the magnets 27, 28 and 29, the armature windings 30, 31 and 32, and the magnet 57 when the power wheel 17 again will be free to rotate independent of the shell 9, and the magnets 27, 28 and 29 will cooperate with the armature windings 30, 31 and 32 to cause the power wheel 17 to rotate in the direction of the arrow 34, see Fig. 2, at a sufficient speed in turn to cause the drum 5 through the associated train of gears to rotate at a faster rate of speed than the rate of speed of the shell 9. On the other hand, when both the switches 188 and 189 are open, not only will the magnets 21 to 23, inclusive, and the magnets 27 to 29, inclusive, and the armature windings 30, 31 and 32 be de-energized, but the magnet 57 will also be de-energized to enable the

spring 55 again to cause the clutch discs 53 and 54 to engage one another and lock the power wheel 17 to rotate with the shell 9. When the magnets 21 to 23, inclusive, or the magnets 27 to 29, inclusive, and the armature windings 30, 31 and 32, inclusive, are energized either to retract or extrude the blades, the switch 188 or the switch 189, as the case may be, will only be held in closed position the period required to retract or extrude the blades 1 the distance required.

In the embodiment illustrated in Figs. 7, 8, 9 and 10, inclusive, in order to further protect the blades from being bent beyond the elastic limit, the blades here bearing the reference character 15 63, are similar in construction to the blades 1 illustrated in the embodiments shown in Figs. 1 to 6, inclusive, and similarly connected to a drum 64 such as the drum 5. However, to protect the blades from being bent by their reinforcing cross pieces 65, such as the cross pieces 4 of Fig. 4, there is provided a protective strip 66 preferably composed of rubber, one strip 66 for each blade 65. The strip 66 as shown in Fig. 7 is connected to the drum 64 directly under the blade 63, that is, between the blade 63 and the drum 64, so that the cross pieces 65 may embed themselves in the yieldable texture of the strip 66 and thus protect the blade from being bent by the cross pieces 65 when the blade in the course of being wrapped on the drum 64 will have one portion of the blade folded on to another portion thereof. In this embodiment the blades 63 when passing outside of the shell 67 will preferably engage a roller such as the roller 68 at the end of a slot between the partitions 69 and 70. The smooth faces 71 of the blades 63, that is, the faces not obstructed by the cross pieces 65, engage the roller 68 as shown in Fig. 7.

These strips 66 are connected at one of their 40 ends as shown in Fig. 7 to the drum 64, and at the other of their ends they are connected to the drum 72 disposed adjacent to the drum 64, the hub 73 of the drum 72 being mounted on the shaft 74 and in the present instance extending radially inward of the drum 64 and engaging the side face of the gear 75. The hub 73 is rotatably mounted on the shaft 74 but is connected by the coil spring 76 to the shaft 74, one end of the coil spring 76, see Fig. 7, being connected to the shaft 74, and the other end of the coil spring 76 being connected in the inner periphery of the drum 72. In order to guide the rubber strips 66 from the drum 64 to the drum 72, they pass over the rollers 77 and 78, which are inclined relative to the axis of the rollers 68 at about 45 degrees. It is, of course, obvious that there will be one set of rollers 77 and 78 for each strip 66 and one strip 66 for each blade 63. In operation, it will appear that when the blades 63 are retracted or wound upon the drum 64 they will advance the strips 66 from the drum 72 against the tension of the spring 76, in which case the drum 64 will rotate in a counter-clockwise direction, see Fig. 7, relative to the shaft 74, in which case the spring 76 will be at least partly wound up and placed under tension. On the other hand, when the blades 63 are caused to extend or extrude from the shell 67, then during the extruding action the drum 64 will rotate in a clockwise direction relative to the shaft 74, permitting the drum 72 to rotate in the same clockwise direction under the tension of the spring 76 to wrap the strips 66 on to the drum 72.

It is, of course, obvious, that with this blade the resultant increase of propeller torque with

decreasing altitude can readily be offset by reducing the radius of the propeller during flight, that is, by causing the blades 1 of the first embodiment and blades 63 of the second embodiment to be partially withdrawn. Since the desired length of propeller blade for a given altitude can readily be pre-determined, it will only be necessary for the pilot to cause the blades to be withdrawn the degree necessary to correspond to the particular altitude attained.

Preferably, the blades 1 are secured to the drum 5 by wires passing through the minute openings 79, the number of openings 79 depending upon the length of blade 1 provided and the thickness of the base 6. With a blade 1 of the dimensions here specified, where the base 6 does not exceed the thickness of the main part of the blade more than three times, then it may be desirable to use a number of openings for the wires not to exceed 20 in number.

It is obvious that various changes and modifications may be made to the details of construction without departing from the general spirit of the invention as set forth in the appended claims.

I claim:

1. In an airplane propeller, the combination of a propeller shaft, and a plurality of torsionally flexible blades extending outwardly from said propeller shaft, each blade having an average thickness not more than one-thirtieth times its average width to give an efficient blade cross-section at supersonic velocities and having a length at least sixty times its average width to make the twisting moment due to centrifugal force less than the aerodynamic twisting forces for the desired range of propeller pitch angles, composed of a metal having a fatigue strength in excess of thirty-one tons per square inch to permit efficient operation at propeller tip velocities up to and greater than the velocity of sound and at forward propeller velocities up to and greater than the velocity of sound.

2. In an airplane propeller, the combination of a propeller shaft, and a plurality of torsionally flexible blades extending outwardly from said propeller shaft, each blade having an average thickness not more than one-thirtieth times its average width to give an efficient blade cross-section at supersonic velocities and having a length at least sixty times its average width to make the twisting moment due to centrifugal force less than the aerodynamic twisting forces for the desired range of propeller pitch angles, composed of quenched and tempered nickel-chrome steel, and formed to enable aerodynamic forces to hold each segment of the blade's length at the desired angle of attack to the air flow, thus to permit efficient operation at propeller tip velocities up to and including the velocity of sound, and at forward propeller velocities up to and greater than the velocity of sound.

3. A torsionally flexible blade for an airplane propeller, extending outward from a shaft or hub and having a length at least sixty times its average width and having an average thickness not more than one-thirtieth times its average width consisting of two strips of metal having a high fatigue strength and formed into two sections fixed in close proximity to one another, one constituting the leading section and the other the trailing section, the front edge of the trailing section placed behind the rear edge of the leading section throughout the entire length of the blade.

4. A torsionally flexible blade for an airplane

propeller, extending outward from a shaft or hub and having a length at least sixty times its average width and having an average thickness not more than one-thirtieth times its average width consisting of two strips of metal having a high fatigue strength and forming two sections fixed in close proximity to one another, one constituting the leading section and the other the trailing section, the leading section having a greater thickness than the trailing section, the neutral axis of the trailing section inclined at an angle to the neutral axis of the leading section.

5. A torsionally flexible blade for an airplane propeller, extending outward from a shaft or hub and having a length at least sixty times its average width and having an average thickness not more than one-thirtieth times its average width consisting of two strips of metal having a high fatigue strength and forming two sections fixed in close proximity to one another, one constituting the leading section and the other the trailing section, the leading section having a greater thickness than the trailing section, the front edge of the trailing section placed behind the rear edge of the leading section throughout the entire length of the blade, and the neutral axis of the trailing section inclined at an angle to the neutral axis of the leading section.

6. A blade for an airplane propeller extending outward from a shaft or hub and consisting of two strips of metal about twelve feet in length forming two parts each about one-half inch in width, the leading edge of the trailing strip placed about three-fourths of an inch behind the trailing edge of the leading strip, the neutral axis of the trailing section inclined at an angle between two degrees and six degrees to the neutral axis of the leading section, each section having a thickness less than .03 inch, composed of a material with a fatigue strength in excess of thirty-one tons per square inch, and with means for connecting the two sections to one another to effect the cross-sectional rigidity of the blade without interfering with its torsional flexibility to permit operation of the blade at propeller tip velocities up to and greater than the velocity of sound and at forward propeller velocities up to and greater than the velocity of sound.

7. A torsionally flexible blade for an airplane propeller extending outward from a shaft or hub and consisting of two strips of metal having a high fatigue strength and forming two sections spaced from one another, one constituting the leading section, the other the trailing section, the over-all length of the blade being about twelve feet, the two sections each about one-half inch in width, the leading edge of the trailing section placed about three-fourths of an inch directly behind the trailing edge of the leading section, and in the same plane as the leading section, the leading section being about .016 inch in thickness, the trailing section being about .007 inch in thickness, the neutral axis of the trailing strip inclined at an angle of about four degrees to the neutral axis of the leading strip, and reinforcing strips extending across and connecting the sections to one another at three inch intervals, said reinforcing strips being about .02 inch by .10 inch in cross-section with the smallest dimension extending in the direction of the blade length, to effect the cross-sectional rigidity of the blade without interfering with its torsional flexibility, to hold each segment of the blade's length at the predetermined angle of attack to the air flow by means of aerodynamic forces, and

thus to permit efficient operation at propeller tip velocities up to and greater than the velocity of sound, and at forward propeller velocities up to and greater than the velocity of sound.

8. A torsionally flexible blade for an airplane propeller extending outward from a shaft or hub and having a length at least sixty times its average width and having an average thickness not more than one-thirtieth times its average width consisting of two strips of metal having a high fatigue strength and formed into two sections spaced from one another, one constituting the leading section, the other the trailing section, and reinforcing cross pieces spaced at intervals along the blade for spacing the sections from one another to effect the cross-sectional rigidity of the blade without interfering with their torsional rigidity to permit efficient operation of the blades at propeller tip velocities up to and greater than the velocity of sound and at forward propeller velocities greater than the velocity of sound, said reinforcing pieces having their greatest dimension in the direction of the blade width, with an extension perpendicular to the face of the blade about seven to fourteen times the thickness of the blade, and with their shortest extension in the direction of the blade length, said shortest extension being about the same as the blade thickness.

9. In an airplane propeller, the combination of a propeller shaft, a plurality of flexible blades extending outward from said propeller shaft, the blades each composed of two thin flexible metal strips of high fatigue strength and formed into a leading section and a trailing section, fixed in close proximity to one another, the leading section being about twice as thick as the trailing section, the front edge of the trailing section placed directly behind the trailing edge of the leading section, and in the same plane as the leading section throughout the entire length of the blade, the distance between the sections being about as great as the width of one of the sections, the neutral axis of the trailing section inclined at an angle between two degrees and six degrees to the neutral axis of the leading section, and means provided for connecting the two sections to one another to effect the cross-sectional rigidity of the blade when operating at propeller tip velocities up to and greater than the velocity of sound and at forward propeller velocities up to and greater than the velocity of sound.

10. The combination of a frame, a driven shaft mounted in said frame, a shell fixed on said shaft, a drum rotatably mounted on said shaft, said shell having a plurality of arcuate guides with spaces therebetween radially disposed to said drum, a plurality of flexible blades connected to said drum and slidably mounted on said guides, and means for operatively connecting said shaft to said drum to enable said drum to withdraw said blades out of extruding position relative to said shell, or to extrude said blades to rotate with said shell as a propeller, each of said blades being composed of two sections, one section constituting a leading section and the other a trailing section, and means for connecting said sections to one another to maintain a predetermined angle relative to one another.

11. The combination of a frame, a driven shaft mounted in said frame, a shell fixed on said shaft, a drum rotatably mounted on said shaft, said shell having a plurality of arcuate guides with spaces therebetween radially disposed to said drum, a plurality of flexible blades connected

to said drum and slidably mounted on said guides, a power wheel rotatably mounted on said shaft, a train of gears for drivingly connecting said power wheel to said drum, an anchor for anchoring said power wheel to said frame while said shaft rotates to enable said drum to be rotated in turn to withdraw said blades into said shell, and a second anchor for arresting said train of gears relative to said shell, when said power wheel is liberated to rotate with said shell, to enable said blades in retracted position to rotate with said shell.

12. The combination of a frame, a driven shaft mounted in said frame, a shell fixed on said shaft, a drum rotatably mounted on said shaft, said shell having a plurality of arcuate guides with spaces therebetween radially disposed to said drum, a plurality of flexible blades connected to said drum and slidably mounted on said guides, a power wheel rotatably mounted on said shaft, a train of gears for drivingly connecting said power wheel to said drum, an electric motivating means operatively connected between said shell and power wheel to actuate said power wheel at a greater speed than that of said shell to enable said drum to be rotated in turn to extrude said blades from said shell in propeller forming position, and an anchor for arresting said train of gears relative to said shell when said power wheel is liberated to enable said blades in extruded position to rotate with said shell in propeller-forming position.

13. The combination of a frame, a driven shaft mounted in said frame, a shell fixed on said shaft, a drum rotatably mounted on said shaft, said shell having a plurality of arcuate guides with spaces therebetween radially disposed to said drum, a plurality of flexible blades connected to said drum and slidably mounted on said guides, a power wheel rotatably mounted on said shaft, a train of gears for drivingly connecting said power wheel to said drum, an anchor for anchoring said power wheel to said frame while said shaft rotates to enable said drum to be rotated in turn to withdraw said blades into said shell, an electric motivating means operatively connected between said shell and power wheel when said anchor is interrupted to actuate said power wheel at a greater speed than that of said shell to enable said drum to be rotated in turn to extrude said blades from said shell in propeller forming position, and a second anchor for arresting said train of gears relative to said shell both when said first anchor is interrupted and when said motivating means is at rest to enable said blades in retracted or extruded position to rotate with said shell.

14. The combination of a frame, a driven shaft mounted in said frame, a shell fixed on said shaft, a drum rotatably mounted on said shaft, said shell having a plurality of arcuate guides with spaces therebetween radially disposed to said drum, a plurality of flexible blades connected to said drum and slidably mounted on said guides, a power wheel rotatably mounted on said shaft, a train of gears for drivingly connecting said power wheel to said drum, an anchor for anchoring said power wheel to said frame while said shaft rotates to enable said drum to be rotated in turn to withdraw said blades into said shell, an electric motivating means operatively connected between said shell and power wheel when said anchor is interrupted to actuate said power wheel at a greater speed than that of said shell to enable said drum to be rotated in turn to extrude said blades from said shell in propeller forming

position, a second anchor for arresting said train of gears relative to said shell both when said first anchor is interrupted and when said motivating means is at rest to enable said blades in retracted or extruded position to rotate with said shell, a control in said frame and means operatively connecting said first anchor, second anchor and motivating means to said control, to be controlled thereby in turn to control the length of blades extended.

15. The combination of a frame, a driven shaft mounted in said frame, a shell fixed on said shaft, a drum rotatably mounted on said shaft, said shell having a plurality of arcuate guides with spaces therebetween radially disposed to said drum, a plurality of flexible blades connected to said drum and slidably mounted on said guides, and means for operatively connecting said shaft to said drum to enable said drum to withdraw said blades out of extruding position relative to said shell, or to extrude said blades to rotate with said shell as a propeller, each of said blades being composed of two sections, one section constituting a leading section and the other a trailing section, and means for connecting said sections to one another to maintain a predetermined angle relative to one another, a second drum rotatably mounted on said shaft, a plurality of protective strips, one strip for each of said blades extending from said second drum to said first drum with each protective strip connected to said second drum, partly to be wrapped around the same when said blades are extruded, and also connected to said first drum, one protective strip between each two successive blades to be wrapped around said first drum when said blades are withdrawn to protect the blades from injury.

16. The combination of a frame, a driven shaft mounted in said frame, a shell fixed on said shaft, a drum rotatably mounted on said shaft, said shell having a plurality of rollers with spaces therebetween radially disposed to said drum, a plurality of flexible blades of quenched and tempered nickel-chrome steel not exceeding .02 inch in thickness connected to said drum and engaging said rollers, and means for operatively connecting said shaft to said drum to enable said drum to withdraw said blades out of extruding position relative to said shell or to extrude said blades to rotate with said shell as a propeller, each of said blades being composed of two sections, one section constituting a leading section and the other a trailing section, and cross pieces not exceeding .02 inch in thickness for connecting said sections to one another to maintain a predetermined angle relative to one another, a second

drum rotatably mounted on said shaft, a plurality of yieldably protective strips, one strip for each of said blades extending from said second drum to said first drum with each protective strip connected to said second drum partly to be wrapped around the same when said blades are extruded and also connected to said first drum, one protective strip between each two successive blades to be wrapped around said first drum when said blades are withdrawn to protect the blades from injury.

17. The combination of a frame, a driven shaft mounted in said frame, a shell fixed on said shaft, a drum rotatably mounted on said shaft, said shell having a plurality of rollers with spaces therebetween radially disposed to said drum, a plurality of flexible blades of quenched and tempered nickel-chrome steel not exceeding .02 inch in thickness connected to said drum and engaging said rollers, and means for operatively connecting said shaft to said drum to enable said drum to withdraw said blades out of extruding position relative to said shell or to extrude said blades to rotate with said shell as a propeller, each of said blades being composed of two sections, one section constituting a leading section and the other a trailing section, and cross pieces not exceeding .02 inch in thickness for connecting said sections to one another to maintain a predetermined angle relative to one another.
